COLLAPSIBLE SEAT ATTACHMENT

Howard W. Zillig, Newburgh, N. Y.

Application February 18, 1947, Serial No. 729,248

7 Claims. (Cl. 155—133)

1

This invention is a collapsible seat attachment readily portable and adapted to be used on grandstand and bleacher seats at baseball and football games, on the seats of row boats and other benches or planks which are not ordinarily provided with back rests.

Attachments of this general character have heretofore been suggested and the object of the present invention is to produce a highly superior article, one which may be collapsed into minimum dimensions and readily set up for use on any appropriate seat with ease and dexterity.

The invention embodies numerous novel features which will be hereinafter more fully described, but, generally stated, it consists essentially of side bars adapted to lie flat upon a board or plank in parallel relation transversely thereof, being provided at their forward ends with hooks to hook over the front end of the seat and at their rear ends with upright side stiles spaced apart by diagonal braces arranged between them. The inclination of the side stiles of the back, with respect to the side bars, is maintained while the device is in use, by appropriate gusset links or chains which may be either fixed or of variable length, to allow of varying the inclination of the back to the most comfortable position for the individual user.

The device of this invention has no seat. The occupant is adapted to be seated directly upon the board or plank to which the device is removably attached, but an appropriate back member of canvas may be stretched between the side stiles of the back if so desired.

The accompanying drawings illustrate different practical embodiments of the invention, but the constructions therein shown are to be understood as illustrative, only, and not as defining the limits of the invention.

Figure 1 is a perspective view showing the preferred form of the present invention associated with a seat shown in phantom.

Figure 2 is a detail view showing the manner of rotatably associating with one another the cross braces of the back shown in Figure 1, one member of the assembly being removed in the interests of clearness. The showing of Figure 2 is in effect a plan view of the structure of Figure 3 with the top circular plate and the bolt removed.

Figure 3 is a section on the line 3—3 of Figure 2.

Figure 4 is a fragmental perspective showing one of the side stiles in the back with a different

2

form of attachment between the lower end of the braces and the side stile.

Figure 5 is a section on the line 5—5 of Figure 4.

Figure 6 is a section on the line 6—6 of Figure 5.

Figure 7 is a fragmental perspective showing substantially one-half of a modified form of this invention embodying arm rests and a somewhat different form of back bracing, with chain braces between the side stiles of the back and the side bars of the seat portion.

Figure 8 is a fragmental perspective detail showing the manner in which the chain illustrated in Fig. 7 may be adjusted as to length to vary the inclination of the back.

Figure 9 is a section on the line 9—9 of Figure 7.

Referring first to Figures 1—3, inclusive, the reference character S indicates the seat of a row boat or the board or plank of a stadium, bench or seat. The device of this invention, as shown in these figures, embodies two side bars 1 which are of identical construction. They may be of wood or metal, but are shown in this embodiment as of wood. Attached to the front end of each of these bars 1 is a hook 2, which may be rotatably attached to the bar, but, in any event, is so shaped as to hook over the front end of the seat S. The rear end of each bar is pivotally secured, as by means of a conventional hinge 3, to an upright side stile 4. The inclination of the side stiles is controlled by gusset brace 5, here shown as comprising two links, the adjacent ends of which are provided with interfitting eyes while the distant ends of the links are passed through the side bars 1 and stiles 4 and headed over, so as to permit the links to pivotally move with respect to the bars and stiles.

The links of each pair are of different length so that the side stiles may be folded down flat against the side bars 1 into neat and compact condition. The unequal length of these links permit this without producing undesirable bulk in the vicinity of the hinges 3 and also permit the attachment of the links of these braces at the most efficient points in the lengths of the side stiles and side bars. These points are unequally distant from the hinges 3.

The side walls 4 are adapted to be normally spaced apart, as shown in Figure 1, by diagonal braces 6. The upper end of each brace is provided with an eye 7 which interfits with another eye 8 fixedly secured to one of the side stiles near the upper end of the latter. The lower end of

each diagonal brace is provided with an eye 9 which embraces an upright guide rod 10, the upper and lower ends of which are anchored in the side stiles. The guides 10 permit the side stiles to be moved toward and away from one another to collapse or expand the back.

In order to maintain the side stiles at all times in parallel relation to one another, the diagonal braces 6 are offset to form arcuate portions 11 where they cross one another, as shown best in Figures 2 and 3 and each arcuate portion is housed within an annular channel 12 in one of two sections 13 and 14 of a circular fitting. The two sections of the fitting are locked together by means of a bolt 15 and in the abutting faces of the fitting the annular channels 12 are formed. The hubs of the fittings interfit, as shown in Figure 3, so as to keep them in axial alignment. With a fitting of this kind, the two braces are adapted for rotary movement with respect to one another, but are secured against relative longitudinal shifting and thus serve to maintain the stiles in parallel relation at all times.

The article may be used as described, if desired, the occupant being seated upon the seat S between the side bars with his back resting against the cross braces. However, a piece of canvas or leather may be positioned to bridge the space between the side stiles of the back with its opposite ends tacked or otherwise secured to said side stiles. The device shown in Figure 3 is set up, as illustrated in Figure 1, but when it is desired to transport the same, it may be folded into compact condition and carried in a relatively small neat case of leather, canvas or other suitable material or packed in a suit case.

The form of the invention shown in Figures 4 to 6 inclusive is the same in all respects as that shown in Figures 1-3, except that, instead of having the lower ends of the cross braces 6 slide on guides 10, as in Figure 1, the structure of Figure 6 provides for a detachable locking of the lower end of each cross brace to the opposite side stile.

Thus, as shown in Figures 4 to 6, the inner edge of each side stile is provided with a notched plate 16 held in place by screws 17 with the notch 18 extending toward the front edge of the plate. Back of the plate, the side stile is chambered to form a passage 19 leading back from the front face of the side stile to a point adjacent the base of the notch 18 and there the chamber extends downwardly to form a locking well 20. The lower end of each diagonal brace 6a, which corresponds to the brace 6, has a downturned end 21 forming a hook.

When the parts of this form of the invention are collapsed, the lower ends of the diagonal braces hang free. To lock it in expanded position, the side stiles are first moved apart and each side stile is turned through 90 degrees to present the open forward end of the passage 19 to the hook 21, so that the hook 21 (shown in phantom in Figure 5) is opposite the open end of the passage. The hook may then be shifted into the passage until its lower end is directly above the well 20. If the hook is then depressed into the well and the side stile thereupon returned to its normal position shown in Figure 6, the portion of the brace 6a immediately adjacent the hook will enter into the notch 18 of the plate 16 and this notch will keep the hook from lifting out of the well and lock the lower end of the brace 6a in this position, so long as the front face of the side stile faces in a forward direction. The

cross braces thus connected to their respective side stiles at their lower ends will lock the side stiles in spaced position while in use. To disengage the lower ends of the braces from the side stiles, the operations described are reversed. An inturned lip 22 on the plate 16 reinforces the forward side of the well 20.

Figures 7, 8 and 9 show a further modified form of the invention. Here the side bars 23, which correspond to the bars 1, are shown as of angle iron. The hooks at the forward ends of these side bars are pivotally secured to the bars, as heretofore, but with provision for locking them in depending position. As shown, each hook 24 is provided with a shank 25, journalled for rotation in two blocks 26 and 27 rigid with each side bar. Between these blocks, each shank is provided with a fixed collar 28 and a spring 29 is interposed between the fixed collar 28 and the block 27 and normally tends to push the shank forwardly. The shank carries near its free end a pin 30 which is seated by the spring 29 in notches 31 formed in the rear face of the block 27 when the hook is in the position shown in Figure 7, to lock the hook in this position. By pressing rearwardly on the spring, the pin 30 may be disengaged from the notches 31 so that the hook may be swung through an angle of 90 degrees and thus permit a more compact construction when collapsed.

The rear end of each bar 23 is pivoted to the lower end of the side stile 32, which corresponds to one of the side stiles 4, by means of a rivet or screw and the angle of inclination of the back may be controlled by means of chains 33, one of which is associated with each side of the device. The lower end of each chain is secured to the corresponding side bar while the upper portion of the chain is adapted to be hooked into a constricted notch 34, formed in a plate 35 carried by the corresponding side stile as shown in Figure 8. The chain 33 may be hooked into this notch to engage selected links of the chain and thus vary the inclination of the back, to suit the occupant.

The structure shown in Figure 7 is provided with arms, one of which is indicated at 36. The rear end of each arm is pivotally secured to the corresponding side stile by means of a screw or rivet while the forward end of each arm is spaced above the corresponding side bar 23 by a spacing link 37. Any of the structures of this invention may be provided with arm rests 36, as shown in Figure 7.

In Figure 7, the side stiles of the back are spaced apart by diagonal braces 38 which may conveniently be made of plywood, sheet metal or any other suitable shape retaining material. The upper end of each brace 38 is pivoted to the upper end of the side stile by means of a rivet or screw 39, while the lower end carries a pin 40 adapted to travel in an upright guide slot 41 in the corresponding side stile. In practice, the slot 41 is preferably formed in a metal plate secured to the side stile and the pin 40 is headed back of such plate, to be held in this position while permitting the pin to slide longitudinally of the slot, so that the structure may be collapsed. The relatively broad braces 38 of Figure 7 are more comfortable than the narrow wires of Figures 1 and 4 and may be used either with or without leather, canvas or other covering as heretofore referred to in connection with Figure 1.

In all of the structures which I have described thus far the side stiles of the back are of wood. If desired, these side stiles may be of tubular

metal construction of any desired cross section and the guides 10 and 41 may be made as slots formed directly in the tubular wall of the sections and extending longitudinally thereof. Pivotal attachments for hinges, pivots, etc. may be made either by screw threading or by welding as will be clearly understood.

In all of the structures of this invention which I have hereinbefore described, the structure is such as to provide for collapsing thereof into convenient, compact, carrying form. Nevertheless all of these structures may be readily extended into a condition for use and when set up in the manner illustrated in Figure 1 to provide a strong durable construction even when used by heavy persons. The structures may be made of wood or metal or part wood and part metal, or organic plastics may be used in their construction. In any event, the device of this invention will prove a great comfort to persons while fishing or while observing sporting events.

The foregoing detailed description sets forth the invention in its preferred practical form, but the invention is to be understood as commensurate with the appended claims.

Having fully described the invention, what I claim as new and desire to secure by Letters Patent is:

1. A collapsible seat attachment comprising: side bars adapted to rest upon and extend transversely of a seat which bars are provided at their forward ends with hooks to hook over the front edge of the seat, side stiles pivoted to the rear ends of said bars, gusset braces for retaining said side stiles at the desired upright inclination, and a single diagonal brace connecting the upper portion of each side stile to a lower portion of the other side stile, the upper ends of said braces having fixed pivots and the lower ends of said braces being adjustably secured to the lower portions of said side stiles, whereby the side stiles may be moved toward and away from one another, said two single diagonal braces being the sole means for maintaining the side stiles in spaced apart parallel relation when the attachment is in use.

2. A collapsible seat attachment comprising: side bars adapted to rest upon and extend transversely of a seat which bars are provided at their forward ends with hooks to hook over the front edge of the seat, side stiles pivoted to the rear ends of said bars, gusset braces for retaining said side stiles at the desired upright inclination, and diagonal braces connecting the upper portion of each side stile to a lower portion of the other side stile, the upper ends of said braces having fixed pivots and the lower ends of said braces being adjustably secured to the lower portions of said side stiles for sliding movement longitudinally of the latter, each of said diagonal braces being provided intermediate its ends with an offset portion housed within a fitting section, said fitting sections being arranged in abutting relation to one another and bolted together for relative pivotal movement while holding said side stiles in spaced parallel relation.

3. A collapsible seat attachment comprising: side bars adapted to rest upon and extend transversely of a seat which bars are provided at their forward ends with hooks to hook over the front edge of the seat, side stiles pivoted to the rear ends of said bars, gusset braces for retaining said side stiles at the desired upright inclination, and a single diagonal brace connecting the upper portion of each side stile to a lower portion of the

other side stile, the upper ends of said braces having fixed pivots and the lower ends of said braces being detachably locked to the lower portions of the side stiles to maintain said side stiles in spaced relation, said two single diagonal braces being pivotally secured to one another at their points of crossing, said two diagonal braces being the sole means for maintaining the side stiles in spaced apart parallel relation.

4. A collapsible seat attachment comprising: side bars adapted to rest upon and extend transversely of a seat which bars are provided at their forward ends with hooks to hook over the front edge of the seat, side stiles pivoted to the rear ends of said bars, gusset braces extending between intermediate portions of the side bars and intermediate portions of the side stiles for controlling the inclination of the side stiles with respect to the side bars, each gusset brace embodying a pair of pivoted links the contiguous ends of which are pivoted to one another at the elbow of the brace with the terminal end of one link permanently anchored by a fixed pivot to one side bar and the terminal end of the other link permanently anchored by a fixed pivot to one side stile, said links being of unequal length to permit of compact folding of the stiles and side bars into substantially face abutting relation while the terminal ends of said links remain pivotally anchored against longitudinal movement to both the side bar and said stile, and diagonal braces extending between the side stiles for maintaining them in substantially parallel relation.

5. A collapsible seat attachment comprising: side bars adapted to rest upon and extend transversely of a seat which bars are provided at their forward ends with hooks to hook over the front edge of the seat, side stiles pivoted to the rear ends of said bars, gusset braces extending between intermediate portions of the side bars and intermediate portions of the side stiles for controlling the inclination of the side stiles with respect to the side bars, each gusset brace embodying a chain one end of which is secured to one of the side bars and the other end portion of which is adapted to be adjustably engaged with a slotted plate carried by the corresponding side stile.

6. A collapsible seat attachment comprising: a back support including upright side stiles connected by a diagonal bracing, a seat side bar pivotally secured to the lower end of each side stile with a gusset brace between each side stile and side bar to hold said side stiles at the desired upright inclination, each side bar being provided at its forward end with a hook to hook over the front edge of a seat, each hook being pivotally mounted on the side bar, and means to lock each hook against pivotal movement, said means embodying a pin carried by the shank of each hook, and a spring embracing said shank and normally engaging the pin with a notch formed in the side bar, each spring being compressible to release the corresponding hook for pivotal movement.

7. A collapsible seat attachment comprising: side bars adapted to rest upon a seat with hooks at their forward ends to engage the forward edge of the seat, and upright side stiles pivoted to the rear ends of said bars, in combination with diagonal braces extending between said side stiles and crossing one another intermediate their ends, said diagonal braces being pivoted to one another at their points of crossing with

their upper ends secured by fixed pivots to the side stiles and their lower ends provided with hooks, each side stile having a locking chamber engageable with the hook on one of the diagonal braces through rotation of the corresponding side stile to detachably lock the hook end of said brace against inadvertent disengagement with said stile.

HOWARD W. ZILLIG.
